UNITED STATES PATENT OFFICE.

RASMUS P. HANSEN, OF KNOB, CALIFORNIA.

COMPOUND TOOL.

No. 918,672.

Specification of Letters Patent.

Patented April 20, 1909.

Application filed January 29, 1907. Serial No. 354,711.

To all whom it may concern:

Be it known that I, RASMUS P. HANSEN, a citizen of the United States, residing at Knob, in the county of Shasta and State of California, have invented certain new and useful Improvements in Compound Tools, of which the following is a specification, reference being had therein to the accompanying drawing.

10 My invention relates to improvements in compound tools and more particularly to one by means of which a farmer or teamster may readily apply or remove the shoes of their horses or otherwise repair any damage that 15 may occur while their teams are on the road.

The object of the invention is to provide a tool of this character which is of simple, strong, durable and comparatively inexpensive construction and which may be effectively used for a variety of purposes.

With the above and other objects in view, the invention consists in the novel construction, combination and arrangement of parts hereinafter described and claimed.

25 In the accompanying drawings Figure 1 is a side elevation of my improved compound tool. Fig. 2 is a longitudinal section taken on the plane indicated by the line 2—2 in Fig. 1, Figs. 3 and 4 are perspective views 30 of the two members of the tool and Fig. 5 is a detail view of the pivotal connection of the levers showing the positions they assume with respect to each other when they are being connected or disconnected.

35 My improved compound tool is in the form of a pair of pincers and consists of two hand levers or members 1, 2, provided with a detachable pivotal connection so that they may be separated to enable them to be used 40 independently or to permit one to be used in connection with the other as presently explained. The members or levers 1, 2 are similar in construction and each comprises a substantially straight-longitudinal tapered 45 handle portion 3, formed adjacent to its larger end with a semi-circular enlargement 4, and terminating at said end in a broad beveled pincer jaw 5. Formed integral with the curved outer end of each of the members 50 or levers is a lateral projection 6 adapted for use as a hammer head. Formed integral with the inner end of the lever 1 is a transversely extending projection 7 having one of its ends tapered to a point 8 to permit it to 55 be used as a punch. The opposite end of the cross piece or projection 7 is enlarged and

rounded to provide an anvil or head 9 in longitudinal alinement with the punch point 8, so that it may be struck by the hammer 6 upon the lever 2 when the two members of 60 the tool are separated. Formed upon the inner end of the lever 2 is a transversely extending enlargement 10 which has one of its longitudinal edges beveled and sharpened to provide a cutter blade 11 which may be used 65 for trimming the hoof of a horse or for other purposes. The opposite longitudinal edge of the enlargement 10 is curved and adapted to serve as an anvil or head 12 which may be struck by the hammer 6 on the lever 1 when 70 it is desired to drive the cutting edge 11 through the object to be cut.

The detachable pivotal connection between the two members or levers is effected by forming upon the semi-circular portion 4 75 of the lever 1 a concentrically disposed and laterally projecting pivot stud 13 having at its outer end diametrically opposed lugs 14 so that said stud is substantially T-shaped. Formed in the corresponding portion 4 of 80 the lever 2 is a circular pivot opening 15 adapted to receive the pivot stud 13 and provided at diametrically opposite points with communicating grooves or recesses 16 to receive the lugs 14. The lugs 14 and the 85 grooves 16 are so arranged with respect to each other that when the jaws are open to their fullest extent the grooves align with the lugs so that by moving one lever laterally 90 with respect to the other they may be separated or connected. In order to enable 95 said grooves and lugs to be properly aligned with each other so that the two levers may be quickly separated, each of the levers is formed at one end of its semi-circular portion 4 with a flat angularly disposed face 17 and at the other end of said portion with a laterally projecting enlargement 18 having an angularly disposed face 19 which is adapted to be engaged by the face 17 of the 100 other lever when the jaws are open to their fullest extent, as shown in Fig. 5. By constructing said levers in this manner, it will be seen that whenever they are open to their fullest extent and their faces 17, 19 are in 105 contact, the grooves 16 will be in register with the lugs 14 so that the levers may be readily engaged with or disengaged from each other by moving one laterally with respect to the other.

110 This combination tool is especially adapted for the use of teamsters and others who fre-

quently have trouble with their horses owing to the loosening and the loss of horse shoes while their teams are upon the road. It will be seen that when the levers are pivotally connected, the pincers 5 may be effectively used as such and that either of the hammers 6 may be conveniently used for driving nails or the like. The pincer blades 5 are made broad and V-shaped in cross section at their edges so that they may be effectively engaged with the bent ends of nails and used as clench cutters. When it is desired to punch a nail from a horse shoe or from the hoof, the levers 1, 2 are separated, the punch 8 is placed upon the nail and the end 9 of the punch is struck by the hammer 6 on the lever 2. Similarly, when it is desired to trim the hoof, the cutting blade 10 is properly placed against the hoof and the opposite end 12 of the cutter is struck by the hammer upon the lever 1. When the members or levers are separated they may be used independently for other purposes than those mentioned.

Having thus described my invention what I claim and desire to secure by Letters Patent is:

The herein described tool comprising two

detachably connected hand levers having coöperating devices, both of said levers having the enlarged semi-circular portions 4 formed at one end of said portion with the stop face 17 and at the other end of the same with the lateral projection 18 having the stop face 19, one of the levers being formed at its center with a circular pivot opening 18, the walls of the latter being grooved at diametrically opposite points, and a pivot stud projecting laterally from the center of the semi-circular portion of the other lever and formed at its outer extremity with oppositely projecting lugs, said pivot stud being adapted to enter said pivot opening and said lugs to pass through said grooves in connecting and disconnecting the levers, said grooves and lugs being adapted to register or aline with each other when the face 17 of one lever engages the face 19 of the other, substantially as set forth.

In testimony whereof I hereunto affix my signature in presence of two witnesses.

RASMUS P. HANSEN.
